DESIGN FOR EMBROIDERED LACE

Jack Goldstein, Bronx, N. Y.

Application September 9, 1937, Serial No. 71,520

Term of patent 3½ years

To all whom it may concern:

Be it known that I, Jack Goldstein, a citizen of the United States of America, residing at the Bronx, in the county of the Bronx and State of New York, have invented a new, original, and ornamental Design for Embroidered Lace, of which the following is a specification, reference being had to the accompanying drawing, forming part thereof.

The figure is a plan view of a portion of embroidered lace showing my design.

I claim:—

The ornamental design for embroidered lace, as shown.

JACK GOLDSTEIN.
